CORE MOLDING APPARATUS

James F. Maine, Cleveland, Ohio, assignor to
 Consolidated Iron-Steel Mfg. Co., Cleveland,
 Ohio, a corporation of Ohio

Application June 1, 1938, Serial No. 211,168

5 Claims. (Cl. 22—10)

This invention relates to molding apparatus and particularly to apparatus for making mold cores.

Core making apparatus is well known in which, after a pair of mating core molds on the apparatus are filled with core material, parts of the apparatus may be hingingly moved; to form gas vent passages in the molded core parts; and to superimpose one of two parts of the core upon the other to make a complete core; and to draw the molds from the core thus formed; and to deposit the formed core upon a dryer device which conforms to the shape of the core to support it while being baked.

In all such apparatus, it is necessary for the hingingly moving parts of the apparatus to register exactly with each other when hingingly moved from one position to another in the operation of the apparatus, in order to accurately register the superimposed parts of the core with each other, and to register the dryer device with the formed core, etc. In prior core apparatus of this class, these registering relations can be obtained only with great difficulty because of defects in the form and arrangement of the parts, and in any case, is soon lost after a relatively short period of use of the apparatus because of the rapid abrasion and wear of the relatively moving parts by the action of the abrasive core making material which unavoidably finds its way into the bearings of the moving parts.

It is one of the objects of this invention to provide an improved apparatus of the class described having bearings for the hingingly movable parts, constructed in an improved manner to resist or prevent such abrasive wear.

Another object is to provide an improved unitary mold support or frame which may be permanently assembled with a mold and constructed to be interchangeable with other like molds and supports, and, at the time of use, being detachably mountable on the main frame of the apparatus for hinging movement thereon in the operation of the apparatus for the purposes described above.

Another object is to provide an improved hingingly movable core mold support, vent mold support, and dryer device support, for an apparatus of the class described.

Another object is to provide an improved spring balanced mounting for a hingingly movable element of a molding apparatus of the class referred to.

Another object is to provide, in an apparatus

of the class referred to, an improved construction of hingingly movable core mold support and an improved hinging bearing therefor.

Another object is to provide generally an improved core molding apparatus of the class referred to.

Other objects will be apparent to those skilled in the art to which my invention appertains.

My invention is fully disclosed in the following description taken in connection with the accompanying drawings in which:

Fig. 1 is a front elevational view of an apparatus embodying my invention;

Fig. 2 is a top plan view of the apparatus of Fig. 1;

Fig. 3 is a view in some respects diagrammatic and illustrating different positions into which hingingly movable parts of the apparatus of Figs. 1 and 2 may be moved in the operation of the apparatus;

Fig. 4 is a sectional view taken from the plane 4 of Fig. 1;

Fig. 5 is a sectional view taken from the plane 5 of Fig. 1;

Fig. 6 is a view similar to Fig. 5 but illustrating parts thereof in different operative positions;

Fig. 7 is a view similar to part of Fig. 2, but drawn to larger scale, and with parts broken away and other parts in section for clearness;

Fig. 8 is a fragmentary sectional view taken from the plane 8 of Fig. 7;

Fig. 9 is a sectional view taken from the plane 9 of Fig. 7;

Figs. 10 and 11 are fragmentary views similar respectively to Figs. 7 and 9, but illustrating a modification;

Figs. 12, 13 and 14 are other views similar to a part of Figs. 7 and 9, respectively, but illustrating another modification;

Fig. 15 is a side elevational view, partly in section of a core which may be made in an illustrative operation of the apparatus of the preceding figures;

Fig. 16 is a sectional view taken from the plane 16 of Fig. 15; and

Fig. 17 is a sectional view taken from the plane 17 of Fig. 15;

Fig. 18 is a view similar to a part of Fig. 4, illustrating a modification.

Referring to the drawings, I have shown at 1 a main base which may be conveniently formed from a steel bar bent into rectangular shape, as shown in Fig. 2, comprising front and back bars 2 and 3 and end bars 4 and 5, the base being

15

20

25

30

35

40

45

50

55

supported upon legs 6—6 in the corners of the frame, which may, as shown in Fig. 4, be made from tubing or pipe and welded into the corners of the base.

5 Secured to the back bar 3 is a pair of hinge brackets 7—7 and spaced therefrom a second pair of hinge brackets 8—8, these brackets being preferably formed from steel angle section, one flange of each angle being secured to the back bar 3, for example by welding, and the other flanges of the angles being slightly spaced apart and in generally parallel relation.

A frame shown generally at 9, and which, as will presently be described, is arranged to support a core vent mold, has a pair of flat bar-like legs 10 and 11 thereon, which are disposed respectively between said pairs of parallel bracket flanges, and hinged thereto by bolts 12 and 13 projecting through perforations in the flanges 20 and in the legs. In the preferred construction, as best shown in Figs. 4 and 5, the bracket flanges are provided with a plurality, such as four, perforations 14—14 of a size to approximately fit the bodies of the bolts 12 and 13; and the legs 10 and 25 11, as shown for the leg 10, in Fig. 4, are provided with a larger perforation 15 into which is press-fitted a bushing 16. By this means, a rotary or hinging movement is provided for the frame 9 and the relative movement occurs between the bushing and the bolt. By removing the bolt and replacing it in one or another of the four 30 perforations 14—14, the position of the frame 9 relative to the other parts of the device may be changed, for a purpose to be described.

35 The legs 10 and 11 have downwardly projecting fingers 17 formed thereon, which, when the frame 9 is in its upper or normal position, illustrated in Figs. 1, 2, 4 and 5, engage the back bar 3 of the base, and function as stops to position the frame. 40 The frame 9 is rectangular in form, as shown in Fig. 1, and is preferably built up from pieces of angle section steel welded together (although to simplify the drawing it is shown as made of solid section bars), and has cross bars 18—18 45 within the rectangle, providing an open work frame upon which core vent molds, shown at 19—19, may be secured in any suitable manner, for example by bolts or screws, not shown, projected through perforations in the frame.

50 The legs 10 and 11 are preferably secured to the lower edge of the frame 9 by welding, and the frame is provided with a handle 21 by which it may be hingingly moved in the operation of the apparatus.

55 A pair of lugs 22—22, Figs. 1 and 5, are secured, for example by welding, to the lower edge of the frame 9, preferably between the legs 10 and 11 and slightly spaced apart, and a link 23 is disposed therebetween and pivotally connected 60 thereto by a bolt or pin 24. The lower end of the link 23 is provided with a perforation 25 into which is hooked the upper end of a tension spring 26, the lower end of which is hooked into the eye of an eye-bolt 27 projected through a perforation 65 in a bracket 28, and adjustably positioned therein to adjust the tension of the spring by nuts 29—29 on the bolt and on opposite sides of the bracket, the body of the bracket extending upwardly and being secured, for example by welding, to the back bar 3 of the base. The spring 26 normally holds the frame 9 in, or returns it to its upper or normal position.

In the operation of the device, to be described, when the frame 9 is hingingly lowered by means 70 of the handle 21, the parts take up the positions

shown in Fig. 6, in which as shown, the spring 26 is stretched. The center line of the spring action, between the pin 24 and the eye of the bolt 27 is, as shown in Figs. 5 and 6, always outward of the axis of the hinge bolts 12 and 13, but as the frame 9 is rocked downwardly, this line of action moves toward the axis, as shown in going from the position of Fig. 5 to that of Fig. 6, so that the frame-returning-force of the spring is maximum when the frame 9 is in its upper normal position. 10

In some uses of the apparatus, it may be desired to shift the position of the frame 9 on the main base, and to this end, hinge brackets 30—30 15 are provided for use with the brackets 8—8 instead of the brackets 7—7, and a bracket 31 is provided for the spring mounting corresponding to the bracket 28.

Upon the front bar 2 is secured, for example by welding, a flat bar post 32, opposite the bracket 20 28, and a similar post 33, opposite the bracket 31; and by a construction to be described, a frame 34 is hinged on an axis 75 to the upper ends of the bracket and post 28—32, and a frame 35 is hinged on an axis 76 to the upper ends of the bracket 25 and post 31—33, and a third frame 36 is arranged to hinge on both the axes 75 and 76. The frames 34 and 35 may be generally similar and comprise front bars 37, back bars 38 and side bars 39 and 40, and the frame 36 likewise comprises front 30 and back bars 41 and 42 and side bars 43 and 44. Within each frame an open frame work is provided by transverse bars 45, or the like, having perforations, not shown, therein through which bolts or screws may be projected to secure upon the frames 34 and 36 core molds, shown at 47 and 48 respectively, and to secure on the frame 35 a core supporting or dryer device, shown at 49.

The frames 34, 35 and 36 may be constructed from angle sections, although they are illustrated 40 for simplicity in drawing, as constructed of solid bars.

The frames 34 and 35 have rearward extensions 50 and 51, and the middle frame 36 has rearward extensions 52 and 53. 45

An illustrative operation of the apparatus thus far described will now be given for making an illustrative core, such as is shown in Figs. 15, 16 and 17, which core comprises upper and lower halves 54 and 55 and a cross-form gas vent duct 50 at 56 therein. The core molds 47 and 48 on the frames 34 and 36 have each a cavity 57 corresponding to the form of the lower and upper halves of the said core respectively, and two vent molds 19—19 on the frame 9 have elevated patterns 58 thereon, corresponding to the shape of the vent duct 56. 55

An operator fills the cavities 57—57 with core making material, which may be sand mixed with an adhesive binder, and strikes off the surplus material flush with the upper surface of the core molds, leaving in each core mold one half of the core with a plane face thereon. The frame 9 is then lowered and the vent pattern 58 is pressed into the faces of the core halves and then the vent mold is withdrawn. Adhesive material is then applied on one or both of the plane faces for gluing them together, or this may be omitted when suitable core mixtures are used.

By means of a handle 59 on the frame 34 and a 70 rod-like handle 60 on the frame 36, these two frames are then lifted and rocked around the axis 75 of the hinge connection for these frames referred to above, the frames moving into the positions shown therefor in Fig. 3. This super-im- 75

poses the two faces of the core upon each other, and, with the faces in engagement, the two frames are rocked together until the frame 36 is in its original position, and then the frame 34 is rocked back to its original position, withdrawing its core mold 47 from the core and leaving the completed and vented core resting on the core mold 48 on the frame 36.

The dryer device 49 on the frame 35 is preferably made from cast iron and has therein a cavity corresponding generally to the shape of the lower half of the core which is now uppermost on the frame 36, and the frames 36 and 35 are now rocked on the axis 76, by means of a bar-like handle 61 on the frame 36 and a loop handle 62 on the frame 35, into the position shown for these frames in Fig. 3, whereby the cavity in the dryer device is fitted over the lower half of the core supported in the core mold 48, and then the two frames are rocked together until the frame 35 is back in its original position, and the frame 36 is rocked back to its original position withdrawing the upper core mold 48 from the core, leaving the core supported upon the dryer device. As an alternative mode of operation, with the completed core resting on the frame 36, the dryer device is placed upon the lower half of the core on the frame 36, and then the frame 35 is rocked over until the frame rests upon the dryer device. Then the two frames 36 and 35 are rocked over together until the frame 35 is in its normal position on the base, and then the frame 36 is rocked back to its original position on the base, withdrawing the core mold 48 from the core, leaving the core supported on the dryer device 49, which is in turn supported on the frame 35.

In the first mode of operation of the dryer device, it must be detachably secured to the frame 35, but in the latter mode of operation it may simply rest loosely thereon. In either mode of operation, the dryer device 34 with the core supported thereon, is then removed to the oven in which the core is baked, to dry and finally finish it.

The construction of the hinging connections on which the frames may be moved as described above, constitutes one of the essential parts of the present invention and will now be described in detail, see Figs. 7, 8 and 9.

The side bar 40 of the frame 35 has detachably bolted thereto a U-shaped member 63 by bolts 64-64 permanently secured to the bar 63 and extending through bores in the bar 40 and having nuts 65 thereon. The member 63 has substantially parallel arms 66-66 extending upwardly at an angle to the bar 40 and in their upper ends are provided with large openings 67-67 in which are axially aligned outer raceways 68-68 of ball bearings.

Socket devices 69-69 comprising each a body portion 70 and a shank 71 of reduced diameter have the shanks projected through each of the inner raceways 72 of the ball bearings, and through axially aligned perforations 73 in the post 33 and bracket 31 respectively, and nuts 74-74 on the shanks rigidly clamp the inner raceways of the bearings between the body portions 70 and the post and bracket respectively.

The frame 35 is by this construction mounted to hinge on the ball bearings around the said axis 76 determined by the axis of the ball bearing. A similar construction is provided for hingingly mounting the frame 34 to rock around the said axis 75 on the post 32 and the bracket 28.

The frame 36, on the right hand side thereof

as viewed in Figs. 2 and 7, has a U-shaped member 77 detachably bolted thereto by bolts 78-78 preferably permanently secured to the member 77 and projected through bores 79-79 in the side bar 44 and in the extension 53 thereof, and secured by nuts 80-80; and arms 81-81 of the member 77 extend upwardly at an angle from the side bar 44 of the frame 36 and at their outer ends have axially aligned bores 82-82 therein through which extends the said rod 60, the rod being secured in the arm ends by set screws 83-83. The opposite ends of the rod 60 extend beyond the arms 81-81, providing trunnions 84-84, which rest in upwardly open recesses 85-85 formed in the upper sides of the body portions 78-79 of the socket devices 69-69. The bottoms of these recesses are circular and co-axial with the axis 76 above referred to, and the trunnions 84 are circular in section and fit accurately in the bottoms of these recesses.

The devices 69, and particularly the body portions 70 thereof, are preferably made from hardened steel as are the trunnions 84 to resist or prevent wear thereof. The bottoms of the recesses 85 open downwardly through bores or perforations 86 whereby dirt or other foreign material which may lodge in the recesses may fall or work downwardly out therefrom.

It will be observed that the socket devices 69 and the rod 60, or at least the trunnion portions 84 thereof, are fabricated separately from the parts with which they are associated which makes it feasible to make them from hardened steel.

The hinge bearings for the middle frame 36 and the end frame 34 on the axis 75 may be made exactly like the one described above for the middle frame 36 and end frame 35 on the axis 76, the parts being supported on the bracket 28 and the post 32.

The arms 81-81 at their outer ends are engaged between the inner ends of the socket devices and axial lost motion is thereby prevented.

By constructing the hinge bearings, as above described, lost motion in the hinge bearings is completely avoided; and the molds, when once they have been accurately positioned on their frame, will register accurately with each other and with the core; and this accuracy of registration will be retained even after a long period of use because of the wear resisting nature of the bearings described.

If, in the operation of the apparatus as above described, the core-making sand or abrasive material should fall into the recess 85, it will readily work out therefrom through the perforations 86 and the rotational planes of the ball bearings being vertical there is little liability that abrasive material will lodge therein; but to insure completely against the admission of abrasive material to either ball bearing, the ball bearing may be sealed by sealing rings 87 and 88, enclosing the balls and races against all admission of abrasive material; and to protect the trunnions 84 and the recesses 85, shields or hoods 91-91 may be provided, formed from sheet metal and welded to the arms 81-81 and comprising hood portions 92-92 which, when the trunnions are in the recesses, completely cover both. Abrasive core material is most likely to fall in the recesses 85 when the trunnions 84 are therein, because it is at such times that the core material is being handled for the making of the cores, and it is only at times when the core material is not being handled that the trunnions are out of the recesses and the recesses uncovered by the removal of the hoods 91.

along with the trunnions 84 and arms 81, so that by the provision of the said hoods, entrance of abrasive material into the recesses is substantially prevented.

5 The construction of the hinge joint for the vent mold frame 9, above described, also prevents the entrance of abrasive material thereto, and substantially prevents wear.

The said bushings 16 and the bolts 12 and 13 10 are preferably made from hardened steel whereby wear is reduced to the minimum and the flanges of the brackets 7-7 and 8-8 fit closely on the opposite sides of the legs 10-11 respectively, whereby dirt or abrasive material is prevented 15 from entering the bearing surfaces between the bushing and the bolt, and any wear which, in the course of time, may occur and cause looseness at these hinging joints can be readily eliminated by removing the bolts and bushings and replacing 20 them with new ones. The bolts are prevented from turning by being drawn up tightly in clamping relation upon the brackets. The bushing 16 is of such length as to fit tightly at its ends between the brackets 7-7.

25 Referring again to the vent mold frame 9, it will be understood that the vent molds 19 used on different production jobs may be of different weights. It is, at the same time, desirable that the operator who moves the frame shall have 30 to exert a predetermined minimum of force and by utilizing the adjustable spring 26 this force may be made the same for the different molds.

When the rearmost holes 14-14 are used for 35 the hinge axis, it may have the effect of causing the frame 9 to incline rearwardly in its normal upper position, when the fingers 17-17 are engaged with the frame back-bar 3, and this may increase the distance which the operator must 40 reach to take hold of the handle 21. When it is desired to cause the frame 9 to be substantially vertical in its normal position for all the molds, this may be accomplished by providing an adjustable stop on the base back bar 3 for the finger 45 17-17 to engage. One form of such adjustable stop is shown in Fig. 18 wherein a screw 93 is threaded through the back bar 3 and fixed in any adjusted position by a nut 94, the outer end of the screw being disposed opposite the finger 17 and engageable thereby.

50 In Figs. 10 and 11 I have illustrated a modification of the hinging bearing of Figs. 7 and 9 respectively. In this form the arm 66 has, on the upper end thereof, an outwardly open recess 95 in which is seated the outer raceway 96 of a 55 ball bearing. In this form the socket device 97 has a shoulder 98 by which the inner raceway 99 of the bearing is clamped upon the inner face of the bracket 31, a portion 100 of reduced diameter on the socket device fitting in and centering the 60 inner raceway.

The recess 85 in the socket device 97 is covered by a hood 92 on the arm 81 as in the first described form. In this form, however, the bearing in the arm 66 is also covered by a hood construction comprising a hood 101, secured, for example by welding, on the upper end of the bracket 31, extending round the curvature of the upper end thereof to points, as at 102 and 103 below the center of the bearing and extending axially inwardly to a point 104, beyond the ball bearing. The hood completely covers the bearing, and the overlapping relation of the hood permits the arm 66 to rock around the bearing under the hood in the operation of the device described above.

75 In a still further modification of this bearing

construction shown in Figs. 12, 13 and 14, the arm 66 on the U-member 63 has in the end thereof a ball bearing which may be similar to that described in connection with the form of Fig. 7. A socket device 106 has a shank 107 extending 5 through the inner raceway 108 of the bearing and a shoulder 109 clamping the said inner raceway upon the bracket 31. A rod 60 secured by the screw 83 in the arm 81 has, outwardly of the arm instead of the solid trunnion of the other forms, 10 a ball bearing thereon comprising an inner raceway 110 fixed upon a reduced diameter end portion of the rod, and an outer raceway 111, the periphery of which is provided with an elevated bead 112. The body portion 113 of the socket 15 device has an upwardly open recess 114 therein the lower portion of which is circular and concentric with the rod 60 and the shank 107 and the upwardly open portion thereof flaring outwardly generally, as at 116. The inner wall of the recess 20 has formed therein a groove 115 substantially fitting the said bead 112.

In the operation of this form, when the rod or handle 60 is raised to rock the frame, the ball bearing on the rod 60 will be withdrawn out of 25 the recess 114 in a manner similar to the withdrawal of the solid trunnion 84, above described for the other forms, and when the frame is rocked to return the rod 60, the ball bearing thereon will accurately seat in the socket device 106, the said 30 groove 115, in the outwardly flaring portions 116-116 thereof, guiding the outer raceway of the bearing to its seat in the recess. The outwardly flaring portions 116 of the groove, may have also, 35 as shown in Fig. 14, laterally flaring side walls 117-117 to further guide or center the outer raceway into its seat in the socket device. The bottom of the recess 114 may be provided with an opening 118, corresponding with the hole 86 in the bottom of the above described recess 85 to 40 allow dirt or abrasive material which may fall thereinto to work out therefrom.

The raceways of the two ball bearings, in the arm 66 and in the socket device 106 may be 45 sealed by the construction of the bearings to prevent the entrance of foreign material to the raceways, but if preferred, both ball bearings may be covered by a hood according to the construction described in connection with the form of Figs. 10 and 11.

50 My invention is not limited to the exact details of construction illustrated and described; changes and modifications may be made within the spirit of my invention without sacrificing its advantages and within the scope of the appended claims.

55 I claim:

1. In a molding apparatus of the class described, a main frame, a mold carrying frame having a hinging connection at each of the opposite sides thereof with the main frame for alternate hinging movement relative to the main frame, said hinging connections comprising a pair of forwardly and rearwardly spaced arms at each side of the mold carrying frame, a pair of bars each projected through aligned perforations in one of the pairs of arms and detachably secured thereto, the bars being parallel to each other and the opposite end portions of each projecting forwardly and rearwardly beyond the arms and being provided with axially aligned 60 cylindrical bearing trunnions, a pair of trunnion socket members corresponding to each bar and having upwardly open sockets with cylindrical bottoms therein and disposed to hingingly support the trunnions in the sockets, the trunnion 65 70 75

- members being detachably mounted on the main frame by means axially aligning the socket bottoms with the axes of the bar trunnions which they support, and the trunnion socket members being disposed outwardly, forwardly and rearwardly of the arms and constituting abutments reacted upon by the arms to prevent forward and rearward shifting of the mold carrying frame.
2. In a molding apparatus of the class described, a main frame, a mold carrying frame having a hinging connection at each of the opposite sides thereof with the main frame for alternate hinging movement relative to the main frame, the said hinging connections comprising a pair of forwardly and rearwardly spaced arms at each side of the mold carrying frame, a pair of bars each projected through aligned perforations in one of the pairs of arms and detachably secured thereto, the bars being generally parallel to each other and the opposite end portions of each bar projecting forwardly and rearwardly beyond the arms and being provided with axially aligned cylindrical bearing trunnions, a pair of upstanding brackets on the main frame corresponding with each bar and provided with axially aligned cylindrical bores, a pair of trunnion socket devices corresponding to each bar and each comprising a head and a cylindrical shank, the heads of the socket devices having each an upwardly open socket with a cylindrical bottom aligned axially with the axis of the cylindrical shank, the shanks being detachably fitted in the bracket bores to dispose the pairs of cylindrical socket bottoms in axial alignment, the trunnions fitting the sockets and the socket bottoms providing axially aligned bearings for the trunnions, the heads being disposed forwardly and rearwardly outwardly of the arms and being reacted upon thereby to prevent forward and rearward shifting of the mold carrying frame.
3. In a molding apparatus of the class described, a main frame, a pair of mold carrying frames having hinging connection with the main frame on a common axis, the hinging connection comprising a pair of brackets extending upwardly from the main frame and spaced apart forwardly and rearwardly, and having axially aligned cylindrical bores therein, trunnion socket members provided each with a head and a cylindrical shank, the shanks being detachably fitted in the bores and the heads being disposed in mutual confronting relation, a pair of bearing elements detachably mounted on one mold carrying frame and rotatably supported on the socket members respectively coaxially with their shanks, means to restrain said one mold carrying frame and the bearing elements mounted thereon from shifting axially relative to the socket members, a pair of arms on the other mold carrying frame, a bar projected through axially aligned bores in the arms and detachably secured thereto, the end portions of the bar projecting outwardly in opposite forward and rearward directions from the arms and constituting axially aligned cylindrical trunnions, the said trunnion member heads having each a socket therein, the bottom of which is cylindrical and axially aligned with the shank and hingingly supporting a trunnion, the arms being disposed inwardly of the trunnion heads and reacting upon the same to prevent forward and rearward shifting of the said other mold carrying frame.
4. In a molding apparatus of the class described, a main frame, a pair of U-shaped members having hinging connection with the main frame on a common axis, the hinging connection comprising a pair of bearing elements mounted in axially aligned bores in the arms of one U-shaped member, trunnion socket members comprising each a head and a cylindrical shank, the shanks being projected through and fitted in axially aligned cylindrical bores provided on the main frame and being detachably secured to the main frame in said bores and the bearing elements being rotatably supported on the socket members respectively, coaxially with their shanks, a pair of arms on the other U-shaped member provided with axially aligned perforations, a bar projecting through the said arm perforations and detachably secured to the arms and projecting oppositely beyond the arms at the end portions of the bar and the end portions being cylindrical and constituting axially aligned cylindrical trunnions, the socket member heads being provided with upwardly open sockets having cylindrical bottoms axially aligned respectively with the shanks, and the bottoms fitting and hingingly supporting the trunnions, and the arms of the second U-shaped member being disposed inwardly of the trunnion heads and reacting upon the same to prevent forward and rearward shifting of the second U-shaped member, and a mold carrying frame detachably secured to each U-shaped member.
5. In a mold carrying apparatus of the class described, a main frame, a mold carrying frame having hinging connection with the rearward side of the main frame, the hinging connection comprising a pair of spaced apart brackets on the main frame each having therein a plurality of perforations the perforations in one bracket being aligned with those in the other bracket in pairs, at least one pair being spaced generally vertically from another and at least one pair being spaced from another in the forward and rearward direction, an arm on the mold carrying frame disposed between the brackets and having a perforation therein, a bearing pin arranged to be detachably projected through a selected pair of aligned perforations in the brackets and through the arm perforation, to hingingly connect the mold carrying frame to the main frame whereby the hinging axis of the mold carrying frame may be selectively adjusted vertically and forwardly and rearwardly, by removing the pin from one pair of holes and placing it in another.

JAMES F. MAINE.
